SWAB FOR APPLYING DISINFECTANTS OR THE LIKE

Howard O. Whamond, Oak Park, Ill., assignor to Plunkett Chemical Company, Chicago, Ill., a corporation of Illinois

Application October 20, 1958, Serial No. 53,049

Term of patent 14 years

(Cl. D9—2)

The dominant features of my design reside in the full line portions of the drawing.

I claim:

The ornamental design for a swab for applying disinfectants or the like, as shown and described.
